Primary Examiner — David G Muller*Assistant Examiner* — Christina Gabrielle Cosden(74) *Attorney, Agent, or Firm* — QuickPatents, LLC;
 Kevin Prince(57) **CLAIM**

The ornamental design for a pulling tool, as shown and described.

DESCRIPTION

FIG. 1 is a top perspective view of a pulling tool, showing my new design;

FIG. 2 is a bottom perspective view thereof;

FIG. 3 is a top plan view thereof;

FIG. 4 is a bottom plan view thereof;

FIG. 5 is a right-side elevational view thereof, the left-side elevational view being a mirror image thereof;

FIG. 6 is a front elevational view thereof; and,

FIG. 7 is a rear elevational view thereof.

The broken lines in FIGS. 6 and 7 represent portions of the pulling tool that form no part of the claimed design.

1 Claim, 5 Drawing Sheets(56)
